(57) **ABSTRACT**

A highchair back support that fills the space behind a small child and the chair back. The back support comprises a seatback cover dimensioned to be slid over the back of a highchair, and a support cushion that is connected to the seatback cover and rests on the seatpad.

9 Claims, 2 Drawing Sheets

FIG. 1

FIG. 2

HIGHCHAIR COVER AND SUPPORT

TECHNICAL FIELD

The present invention relates generally to chair covers and supports, and, more specifically, to a highchair back support for supporting a child in an upright position and for preventing a child from sliding out of a highchair.

BACKGROUND ART

Highchairs are designed for a wide age range of children, from a young infant up to an age just before the child is old enough to sit on its own in a regular or booster chair. Younger children are often too small to sit in a highchair without additional back support to urge their bodies to the front of the highchair. Consequently, parents must often use a rolled-up towel, article of clothing or other cloth to position between the child and the seatback of the highchair.

Prior art seatback covers are designed either to protect the surface of the chair or to improve the aesthetic appearance of the chair. A laminated chair protector may be found by reference to U.S. Pat. No. 3,504,941 to Gerard. This design uses front and back panels of laminated paper to protect the finish of the chair in shipping, handling and/or storage.

The seatback cover in U.S. Pat. No. 4,232,898 to Bodrero uses front and back panels as well as side panels to conform to a vehicle-type seatback. However, in light of the present invention, the aforementioned designs are deficient in that they do not provide back support that fills the extra space left in a highchair occupied by a small child.

It is readily apparent that a new and improved highchair back support is needed that supports a child in an upright and upfront position and prevents the child from sliding therefrom. It is, therefore, to the provision of such an improvement that the present invention is directed.

BRIEF SUMMARY OF THE INVENTION

Briefly described, in a preferred embodiment, the present invention overcomes the above-mentioned disadvantages by providing a highchair back support that fills extra space left in a highchair when a small child sits therein and supports the back of the child to prevent the child from sliding. Generally, the present invention, in the preferred embodiment, comprises a seatback cover, which slides over the back of a highchair and a support cushion, which removably attaches to the seatback cover.

More specifically, the seatback cover comprises front and back panels, which are joined on three sides, leaving an opening at the bottom of the cover. The seatback cover is easily slid over the back of the highchair and secured into position via hook-and-loop fastener. Hook-and-loop fasteners are also attached to the support cushion, and mating hook-and-loop fasteners are attached to the sides of the seatback cover, thereby allowing the support cushion to be removably attached to the seatback cover.

In an alternate embodiment, a single sheet of material is used to construct the seatback cover. The sheet of material is folded to form front and back panels, the front and back panels are then joined along its edges, wherein the bottom of the seatback cover remains open so that the cover can be slid over the seatback of the highchair as described in the preferred embodiment. In another alternate embodiment, the cushion can be secured to the seatback cover using ties, buckles, straps or any other suitable attaching means.

A feature and advantage of the present invention is to provide a new and improved highchair back support that prevents a child from sliding from a highchair.

Another feature and advantage of the present invention is to provide a new and improved highchair back support that is portable thus making it suitable for use at restaurants and other locations.

Another feature and advantage of the present invention is to provide a new and improved low cost highchair back support for young children.

These and other objects, features and advantages of the invention will become more apparent to one skilled in the art from the following description and claims when read in light of the accompanying drawings.

BRIEF DESCRIPTION OF THE FIGURES

FIG. 1 is a perspective view of the present invention according to a preferred embodiment.

FIG. 2 is a perspective view of the seatback cover of the present invention according to a preferred embodiment.

DETAILED DESCRIPTION OF THE PREFERRED AND ALTERNATE EMBODIMENTS

In describing the preferred embodiment of the present invention as illustrated in the figures, specific terminology is employed for the sake of clarity. The invention, however, is not intended to be limited to the specific terminology so selected, and it is to be understood that each specific element includes all technical equivalents that operate in a similar manner to accomplish similar functions.

With regard to all such embodiments as may be herein described and contemplated, it will be appreciated that optional features, including, but not limited to, aesthetically pleasing coloration and surface design, and labeling and brand marking, may be provided in association with the present invention, all without departing from the scope of the invention.

Referring now to FIGS. 1 and 2, device 10 generally comprises seatback cover 20 and support cushion 50. More specifically, seatback cover 20 comprises front panel 22 and back panel 32. Front panel 22 and back panel 32 are constructed of a durable, non-stretchable fabric material cut to the approximate dimensions of a typical highchair A seatback configuration. Therefore, the width of front panel 22 and back panel 32 will approximate the width of the highchair A seatback.

Front panel 22 comprises first end 24, second end 26, third end 28, fourth end 30, inner surface 31a and outer surface 31b. Back panel 32 comprises first end 34, second end 36, third end 38, fourth end 40, inner surface 41a and outer surface 41b. Front panel 22 is fixedly attached to back panel 32 on three sides as more fully described below, preferably by stitching or any known means within the art. First end 24 of front panel 22 is fixedly attached to first end 34 of back panel 32. Second end 26 of front panel 22 is fixedly attached to second end 36 of back panel 32. Third end 28 of front panel 22 is fixedly attached to third end 38 of back panel 32.

Opening 42 is defined by fourth end 30 of front panel 22 and fourth end 40 of back panel 32. Seatback cover 20 is slid over the seatback of the highchair through opening 42 and is secured to the highchair by removably connecting fourth end 30 of front panel 22 and fourth end 40 of back panel 32 under the seatback of the highchair by any means known within the art such as, for exemplary purposes only, buttons, ties, buckles, hook-and-loop fastener or the like.

Preferably, first securing fastener 44 and second securing fastener 46 comprise hook-and-loop fasteners. First securing

fastener **44** is fixedly attached to inner surface **31a** of front panel **22** proximal to fourth end **30**. Mating second securing fastener **46** is fixedly attached to inner surface **41a** of back panel **32** proximal to fourth end **40**. First securing fastener **44** and second securing fastener **46** are attached to first panel **22** and second panel **32**, respectively, preferably by gluing, stitching or any known means within the art. First securing fastener **44** and second securing fastener **46** are preferably positioned directly across from and aligned with each other to allow seatback cover **20** to be secured under the seatback of highchair A.

First seatback fastener **70** and second seatback fastener **72** are provided for removably securing support cushion **50** to seatback cover **20**. Preferably, first seatback fastener **70** and second seatback fastener **72** comprise one portion of hook-and-loop fastener, wherein the mating portion of hook-and-loop fastener is attached to support cushion **50** as more fully described below. First seatback fastener **70** and second seatback fastener **72** are fixedly attached to outer surface **41b** of back panel **32** proximal to first end **24** and third end **28**, respectively, by glue, stitching or any known means within the art.

Support cushion **50** is preferably an elongated triangular cross-sectional shaped member comprising insert **50a** and cover **50b** having first surface **51**, second surface **52**, third surface **53**, first end **54** and second end **56**. Insert **50a** is preferably foam but may be formed from any suitable material known within the art. Surfaces **51**, **52**, **53**, and ends **54** and **56** are constructed, preferably, of fabric material cut to the approximate dimensions of a typical highchair A seatback configuration. Therefore, the width of surfaces **51**, **52**, and **53** approximates the width of the highchair A seatback. The height of surface **51** will preferably approximate one-third to one-half the height of the highchair A seatback. In an alternate embodiment, however, the height of surface **51** may be greater or less than the preferred height.

Support cushion **50** is attached to back panel **32** of seatback cover **20** by any means known within the art such as, for exemplary purposes only, ties, buckles, hook-and-loop fastener or the like. First cushion fastener **74** is attached to first end **54**, and second cushion fastener **76** is attached to second end **56**, preferably by glue, stitching or any known means within the art. First cushion fastener **74** and second cushion fastener **76** preferably comprise hook-and-loop fastener portions mating to those of first seatback fastener **70** and second seatback fastener **72**, respectively, such that support cushion **50** is removably secured to seatback cover **20** when first cushion fastener **74** is mated with first seatback fastener **70** and second cushion fastener **76** is mated with second seatback fastener **72**. Alternatively, ties, buttons, snaps or any known attaching means can be utilized to secure support cushion **50** to seatback cover **20**.

In use, seatback cover **20** is slid over the seatback of the highchair A. Seatback cover **20** is secured by drawing fourth end **30** of front panel **22** and fourth end **40** of back panel **32** underneath the highchair A seatback and attaching first securing fastener **44** to second securing fastener **46**. Support cushion **50** is placed on highchair A seat with first surface **51** oriented toward seatback cover **20**, second surface **52** oriented toward the highchair A seat, and third surface **53** oriented toward the back of the child. Support cushion **50** is secured to seatback cover **20** when first cushion fastener **74** is attached to first seatback fastener **70** and second cushion fastener **76** is attached to second seatback fastener **72**.

It should be noted that in an alternate embodiment, seatback cover **20** may be formed from a single sheet or

blank of material. Although, washable cloth is the preferred material for seatback cover **20**, other materials such as, for exemplary purposes only, plastics, leather or rubber may be utilized. It should also be noted that the dimensions of seatback **20** and support cushion **50** may be varied, as needed, depending on the dimensions of highchair A, the size of the child or the capabilities of the child.

Having thus described exemplary embodiments of the present invention, it should be noted by those skilled in the art that the within disclosures are exemplary only, and that various other alternatives, adaptations, and modifications may be made within the scope of the present invention. Accordingly, the present invention is not limited to the specific embodiments illustrated herein, but is limited only by the following claims.

Having described my invention, I claim:

1. A highchair back support for use on a highchair having a seat, a seatback having a height, a width, a first side and a second side, said highchair back support comprising:

a seatback cover dimensioned to slide over the seatback of the highchair, the seatback cover having a front panel and a rear panel joined together to form a channel therebetween for receiving the seatback of the highchair, the front panel and the rear panel each having adjacent lower edges, the channel having a width greater than the width of the seat back, and a height at least as great as the height of the seatback; a removable cushion support disposed on the seat of the highchair;

means for releasably connecting said cushion support to said seatback cover;

said connecting means including a first attachment member connected to and located adjacent the lower edges of the front and rear panels along said first side of the seat back, and connected to the cushion support;

a second attachment member connected to and located adjacent the lower edges of the front and rear panels along said second side of the seatback, and connected to the cushion support;

a third attachment member attached to and adjacent the lower edges of the first and second panels in a position between the first and second attachment members and under the seatback; and

wherein said cushion support is positionable on the high chair seat between the seatback of the highchair and a child.

50 2. The highchair back support of claim 1, wherein said cushion support is foam.

3. The highchair back support of claim 1, further comprising a cover carried over said cushion support.

4. The highchair back support of claim 1, wherein said cushion support is elongated and triangular shaped.

5. The highchair back support of claim 1, wherein said connecting means includes hook-and-loop fasteners.

6. The highchair back support of claim 1, wherein said connecting means includes at least one button.

60 7. The highchair back support of claim 1, wherein said connecting means includes at least one snap.

8. The highchair back support of claim 1, wherein said connecting means includes at least one tie.

9. The high chair back support of claim 1, wherein said connecting means includes at least one buckle.
